HARRY FROW COGGON, OF HALIFAX, ENGLAND

APPARATUS FOR PLAYING GAMES

Application filed May 10, 1928, Serial No. 276,735, and in Great Britain May 19, 1927.

The present invention relates to apparatus for playing games.

The object of the present invention is to provide a game which will be of an instructive nature in that in the playing of the game the relative geographical location of cities, suburbs and the like is automatically brought to the notice of those participating in the game.

10 A toy has previously been suggested which consists of a number of grooved members adapted to be connected together and to form a circuitous path, each of these grooved members having a single groove on its upper surface extending substantially across the whole width of the member so that the ball placed in the groove at one end of the toy can be rolled to the other end of the toy, the length of the path being increased 15 as additional members are added to the circuit.

20 A toy railway is also known in which toy trains are adapted to run on rails which are formed in foundation members. In this case 25 however, each foundation member is slightly greater than the width between each pair of rollers forming a single track so that such rails can only be joined together at their ends.

25 The present invention has for its object the provision of a game whereby a number of tracks are mounted on a foundation member, these tracks being formed in all directions. The foundation member itself may 30 have sufficient tracks thereon to enable the game to be played without the aid of additional foundation members but if desired a number of foundation members may be connected together at their edges to form a 35 greater area over which toy vehicles may be run.

40 According to the present invention a foundation or base member has tracks formed or mounted thereon consisting of grooves, guides, rails or the like, one or more of which are adapted to intersect one or more edges of the foundation or base member.

45 Each foundation or base member may consist of one or a plurality of sections so that when these sections are connected to-

gether, the guides, grooves, rails or the like intersecting the edges of such sections are adapted to coincide so that a single guide, rail, groove or the like may be continued over a plurality of sections.

50 Each base or foundation member may be shaped according to a certain section of the map of the British Isles or any other country, town or continent; or further, each foundation member may have a section of such a map formed thereon, whilst the tracks in the form of guides, rails or grooves may be utilized to indicate routes from town to town or suburb to suburb as the case may be.

55 Small models of motor vehicles or the like are caused to travel along these grooves. At predetermined points according to the disposition of the roads, further roads represented by grooves or raised portions forming grooves branch therefrom, and as will 60 be readily understood the laying or providing of a sufficient number of grooves or raised portions forming grooves may result in a network of roadways representative of the particular continent, country or town 65 desired.

70 Means may be provided at the termini or cross or branch roads to effect the arrest and release of the vehicles, and to also alter the direction of travel of the said vehicles from 75 one roadway to another when desired, as for example by means of revolvable turntables, by the use of which the vehicles can be turned in such manner as to face a direction in which it is further desired to travel. Incorporated 80 with, or operating in conjunction with such turntables means are provided to effect the stopping of the vehicles on the turntables, whilst the same are being revolved to suit a particular direction, and further means are 85 provided to enable the vehicle to be released when the desired movements of the turntables have been effected.

90 It is not essential that the revolvable turntables shall be placed at a junction of a series 95 of roads, as in the case of a single road having branch roads leading therefrom a suitable form of switch may quite effectively be provided in place of and in substitution of the revolvable turntable provided at the junc- 100

tion of a greater number of roads, or alternatively in the case of two roadways crossing each other the groove or raised portions forming such grooves may be provided in known manner as will allow vehicles to pass along and across either road without the necessity of a turntable or switch. Means are also provided at the end of branch roads to effect the arrest of the vehicle.

10 The invention is more particularly described with reference to the accompanying drawings, in which:—

15 Figure 1 is a plan view of a number of sections joined together to form a map of the British Isles, these sections having routes formed thereon according to the present invention.

20 Figure 2 is a sectional view in elevation showing one form of groove indicating a route on the map.

25 Figure 3 is a modified form of construction.

Figure 4 is a further modification.

25 Figure 5 is a view showing the employment of angle irons acting as a guide for the vehicles employed in the game.

30 Figure 6 is a plan view of a revolvable turntable utilized for changing direction of the vehicles at crossroads.

35 Figure 7 is a corresponding sectional elevation.

35 Figures 8-11 are diagrammatic representations of various positions of the vehicle as it reaches the turntable showing how the change of direction is effected.

40 Figures 12-14 show a construction where the vehicle wheels are adapted to be angularly displaced to steer the vehicle at cross roads, the construction eliminating the necessity of the revolvable turntable at the cross-roads.

45 Figures 15-19 show details of an aeroplane and the method by which it is propelled along tracks formed on the base board or foundation member.

Figure 15 is a front elevation.

Figure 16 is a side elevation.

Figure 17 is a plan view.

50 Figure 18 is a view similar to that of Figure 16 but with the aeroplane in its position of rest at a junction.

55 A representation of a portion of Great Britain is shown in Figure 1 and consists of a base or foundation member built up of a series of sections or blocks 20 of a number suitable for the particular size of game desired, in the instances shown, nine, suitable securing means, not shown, for holding or clamping the blocks together are provided and may be of any known form. Upon the blocks, and in geographical relation, are situated cities or towns 21 connected together by roadways 22.

65 Various methods may be employed for constructing these roadways, as for example in

Figure 2 the base member 20 is formed with a single groove or depression 23 slightly greater in width than the wheel base of the vehicle 24 and of a depth sufficient to satisfactorily guide the vehicle.

70 Instead of a single groove as in Figure 2 parallel grooves for each pair of wheels may be provided as shown in Figure 3, whilst in the case of a base member having incorporated with it raised portions 25 denoting the contour of the country as shown in Figure 4, either the wide single grooves or two parallel grooves may form a portion of the means for providing the contour. In the modified form of construction shown in Figure 5 angle shaped members 26 are secured to the base member 20 and form raised grooves for the reception of the wheels of the vehicle, again these formed grooves may either be situated externally of the vehicle base or a pair of angle shaped members may be provided, one for each wheel.

75 It is obvious that any form of base or foundation member may be used. This may be in the form of a plurality of blocks or sections, the upper surface of which stands out similarly to a relief map. On the other hand the guides, grooves, rails or the like may be placed upon an ordinary map having the position of cities, suburbs and the like indicated thereon in any desirable manner. Further, where grooves are adopted for guiding the toy vehicles, either in the case of grooves having a width equal to a wheel base or parallel grooves each having a width slightly greater than one wheel of the vehicle, the grooves may be mounted in sections on any foundation member such as a floor of a room.

80 Referring again to Figure 1, at each of the cities or towns shown are provided turntables 27 capable of being rotated by remote controls 28. These turntables, Figures 6 and 7, each consist of a circular plate 29 having a turned up edge 30 and are located in the base members 20 on the plates 27, and capable of moving with said plates are pivotally secured two arms 31 forming a wedge or block, held normally in the position shown by a spring 32. Pivotally secured to the base 20 is an arm or lever 33 carrying a circular cone shaped member 34 positioned under the two arms 31, whilst at its other end is secured a cord 35 passing over a guide pin 36 and attached at its other end to a lever 37 mounted in a bracket 38 forming the remote control for the function of the cone shaped member as will be later explained.

85 The rotation of the turntable is effected in the instance shown by means of a band 39 passing around a groove 40 on the underside of the plate 29 and again passing around a similar groove on a pulley 28 (see Figure 1) situated remotely to the turntable.

90 On the motor vehicle shown provision is made to enable the same to be arrested by

contact with the arms of the wedge or block 31 when desired, and in the instance shown this is accomplished by making the rear or driving wheels of a greater width than the front or nondriving wheels, this additional width being denoted by the broken line 41 in Figure 7, i. e., the effective wheel base between the inner edges of the rear wheels is smaller than the corresponding effective front wheel base.

The operation of the turntable is as follows:—

Assume firstly that it is desired that the vehicle shall pass straight over the turntable from one roadway to another roadway opposite, or substantially opposite, this is effected as shown in Figure 7 wherein the width of the two arms 31 forming the wedge or block are in their inoperative position i. e., of a width less than the width of the rear or driving wheels of the vehicle, and correspond to the position of the remote control lever 37 as shown.

If it is desired that the vehicle shall be arrested on the turntable, the operation of moving over the lever 37 to the position 37a results in the displacement of the cord connecting the same with the arm or lever 33, whereupon the arm or lever 33 is swung about its pivot, thereby forcing the cone shaped member 34 between the two arms 31 and causing them also to swing about their pivot against the action of the spring 32 until they are of a greater width than the width between the rear or driving wheels of the vehicle, so that on the vehicle making contact therewith the rear or driving wheels will become wedged against the arms 31 and so effect the arrest of the vehicle as will be apparent.

If the turntable is now revolved by the means previously described the vehicle thereon will also be rotated to suit a desired direction, and should the lever 37 be now returned to its original position the cone shaped member 34 on the lever 33 will be returned to its original position also, whereupon the two arms 31 will be drawn together by the spring 32 and so effect the release of the rear or driving wheel, the vehicle now being free to move in the desired direction.

Having now described the operation of the turntables situate at the representative cities or towns shown in Figure 1, reference is made to Figures 8 to 11, wherein six roadways are shown as being equally spaced round a turntable 27, a vehicle 42 indicated by the four wheels in broken line is approaching the turntable from the roadway 43 and since, as has already been explained, if the two arms 31 forming the wedge are inoperative the vehicle will be capable of passing over the turntable and proceeding along the roadway 44 directly opposite.

Referring to Figure 9 it is assumed for explanatory purposes that the remote control

37 effecting the operation of the parts forming the wedge 31 have been moved to the position denoted by 37a in Figure 7 resulting in the two arms 31 opening out as indicated, and since, as has already been explained, the rear or driving pair of wheels of the vehicle being of greater width than the front pair the travel of the vehicle over the arms of the wedge 31 result in the motion of the same being arrested by the wedging of the rear or driving wheels on the extended arms 31 as shown.

Further, assuming for purposes of illustration, that it is desired that the vehicle should proceed along the road 45 the control for the turntable shown in Figure 1 is rotated whereby the said turntable is correspondingly rotated through the band 39 until the front of the vehicle is substantially in line with the desired roadway as shown in Figure 10, meanwhile the arms 31 of the wedge are still holding the rear or driving wheels of the vehicle from rotating, whereupon if the release operation of the lever 37 controlling the wedge be now made the rear wheels of the vehicle will become free to rotate and the vehicle proceed along the desired roadway 45 as indicated in Figure 11.

It will be apparent that by providing and operating a suitable number of turntables, crossings or the like having a number of roadways converging therefrom, according to the desired roadways leading from a corresponding number of cities or towns a game is provided having geographical interest irrespective of the interest derived in the operation of the various turntables, switches and the like.

The details of construction of the various parts so far described may be varied in many ways, as for example, instead of arresting the motion of the vehicle on the turntable by the action of the wedge or block gripping the inside of the rear or driving wheels the wedge or block may be so constructed as to effect the arresting of the vehicle by gripping from the outside as will be readily understood. Further, whilst in the previous description of a practical example of the invention it has been assumed that the propelling means for the vehicle is effected by a clockwork motor self contained with the vehicle, it will be apparent that an electric motor may be substituted, either having its own propelling means in the form of a battery or the like self contained on the vehicle, or alternatively a separate groove or rail be provided in conjunction with a collector on the vehicle, the supply of energy being thereby external of the vehicle.

Suitable contacts may also be provided so as to temporarily discontinue the supply of energy to the vehicle whilst the turntable is being operated. Further any suitable means

may be provided to effect the opening or closing of the levers forming the wedge or block on the turntable in substitution for that described in the practical example.

5 In a modified form of construction the details of which are described with reference to Figures 12 to 14, the turntable is eliminated and the front wheels of the vehicle are steered by a remote control.

10 In Figures 12 and 13 the front wheels 46 of the vehicle are mounted on stub axles 47 connected together by a link 48, a pin 49 on the link 48 engaging in a slot 50 on one arm 51 of a yoke member pivoted at 52 to a fixed part 15 of the frame work of the vehicle. To one of the remaining arms 51a of the yoke member is attached a spring 53 whose other end is anchored to a fixed part of the framework of the vehicle, the remaining arm 51b of the yoke member being connected by means of a flexible lead or Bowden cable 54 of suitable length to a remote control 54a adapted to be held by the hand of a person and provided with a finger control 55.

20 25 The operation of the control is as follows:—

In order to cause the model to be propelled in a straight line without any change of direction the finger control 55 is depressed to 30 half its full extent which causes the wheels to take up a position shown in dotted lines in Figure 13. When however, the cross roads is reached, the finger control is either released, whereupon the spring 53 causes the wheels to 35 take up the position shown in full lines in Figure 13 which causes the vehicle to turn in one direction, or alternatively the finger control 55 is completely depressed (Fig. 12) which causes the wheels to take up the position 40 on the opposite side of the dotted line position which ensures the vehicle turning in the opposite direction.

It will thus be seen that while the vehicle 45 is travelling along the grooves, the finger control 55 is partly depressed unless the depth of grooves themselves is sufficient to cause the model vehicle to be retained therein. When the vehicle reaches the cross roads, the finger control 55 is actuated by either complete depression or release according to whether the vehicle should turn either to the right or the left.

Suitable stops 66 are provided to limit the 55 extreme movements of angularity of the wheel. Figure 14 illustrates a modified arrangement and provides means suitable for effecting the control of the vehicle, having the front or steering wheels connected by a member 56 pivoted at 57 to the framework of the 60 vehicle. A spring 58 attached at one end and having its other end attached to the framework of the vehicle normally tends to hold the front or steering wheels in the position shown in full line, the remote control 59 65 having arms which are displaced similarly to

the arms of a pair of pliers. This device is adapted to be held in the hand of a person, and consists of two members 60 and 60a pivotally connected together, the former being attached to the core 61 of the flexible connection or Bowden cable whilst the other member is attached to the sheath 62 of such flexible connection. The operation of the control is as follows—the two members 60 and 60a are caused to be opened out by the pressure of the hand of the person on their arms or shanks 63 and 64 whereupon the core of the flexible connection is displaced in respect to its sheath, resulting in the member 56 carrying the front or steering wheels being suitably swung about its pivot 57 to suit the desired direction of travel. Stops 65 attached to the framework of the vehicle form limits for the angular displacement of the wheels.

A further development within the scope 70 of the invention is provided by substituting models of aeroplanes, dirigibles or the like, for models of motors or similar road vehicles previously ascribed. In this development it will be obvious that the disposition 75 of such aeroplanes, dirigibles, or the like, should when in motion, be located at a height or distance from the base member, representing, as in the previous example, a continent, county or town, and this is accomplished 80 by providing rails, grooves, or wires, forming a track mounted or supported on posts or standards, suitably attached or secured to the base member. Means are also provided to effect the arrest and release of the aeroplanes, dirigibles and the like, say at a junction of a series of representative air-roads 85 or airways, as are also suitable turning means for altering the directions of further travel 90 of such models.

One practical example of the development 95 of the invention as above described is shown in Figures 15 to 19, whereby a toy aeroplane 67 having an electric motor 68 self contained, is provided with a propeller 69 attached to the motor in any suitable manner for the 100 propulsion of the model along grooved rails 70 secured conveniently to posts or standards 71, the lower ends of which are attached to the base member (not shown).

Collectors 72 on the model are adapted to 105 contact with portions of the grooved rails 70, one grooved rail having incorporated with it a further rail 75 to which is attached the positive lead of the electrical energy 110 from the source of supply.

This further rail is mounted in insulating 115 material 73 in such a manner as will effectively provide against electrical leakage between itself and the grooved rail 70.

One grooved rail 70 is adapted to be attached to the negative lead of the electrical 120 energy from the source of supply. Suitable springs 74 are provided on the ends of the 125 collectors to ensure closeness of contact.

Attached to the collectors 72 are wires or leads 76 connecting up the circuit of electrical energy with the electrical motor. Rollers or wheels 77 of suitable material are provided to enable the model to be guided, when in motion, along the grooved rails 70 forming the track, as will be apparent.

To effect the arrest of the model at say the junction of a series of air-roads or airways, an arresting medium is provided in the form of a solenoid 78 connected by appropriate means to the source of electrical supply. A core 79 has formed or incorporated with it at one end a plate 80 provided with tapered sides leading to a depression 81 located substantially in the centre of the said plate. The other end of the core is also provided with a flanged end, and between such flanged end and the body 20 of the solenoid a spring is provided so as to normally hold, when the electrical supply is disconnected, the core of the solenoid in the position shown in Figure 16, this position allowing the models to be capable of passing over the plate 80 without contact therewith. When, however, the electrical energy is connected, the core of the solenoid is displaced, whereupon the plate 80 is caused to be lifted to the position indicated in Figure 18, the spring attached to the core being thereupon compressed.

Incorporated with the model is a projection 82 and it will be obvious that when the electrical energy is connected with the solenoid, the plate 80 thereupon being lifted the projection 82 on the model will, in passing over this plate, first strike the tapered portion, and so materially arrest the progress of the model until the projection 82 becomes 40 located in the depression 81 whereupon the full arrest of the model is effected.

Meanwhile the electrical energy for the propulsion of the model being still operative, on release of the electrical energy for the 45 solenoid the plate 82 will be returned to the position shown in Figure 16, thereby allowing the model to proceed under its own propelling means.

The arresting means as described may be 50 incorporated in the form of a turntable similar in principle as regards the rotating means to that previously described for the car or road vehicle, but instead of being, in the base member, it will be mounted in suitable manner to register with the grooves or rails forming the overhead track for the aeroplane.

It will be obvious that a clockwork motor 60 may be substituted for the electric motor just described. This motor either being capable of driving the propeller or being connected to the wheels running in the grooves, and in the latter case the arresting and turning means in the form of a turntable may be

substantially as that described for a road vehicle.

Further, whilst groove tracks have been mentioned as forming the supporting means for the aeroplane, wire or similar members 70 may quite conveniently be substituted.

I declare that what I claim is:

1. Apparatus for playing a game including a foundation member formed of a plurality of sections, tracks formed on said sections running in more than one direction, the tracks of one section coinciding at the edges of the section with the tracks formed in an adjacent section, a mechanically propelled toy adapted to pass along said tracks from a position in one section to any desired position on any other section of the foundation member and junctions at various points of said tracks so that said toy may pass from one track to another as desired. 85

2. Apparatus for playing a game including a foundation member formed of a plurality of sections, tracks formed on said sections running in more than one direction, the tracks of one section coinciding at the edges 90 of the section with the tracks formed on an adjacent section, a mechanically propelled toy adapted to pass along said tracks from a position in one section to any desired position on any other section of the foundation member, a plurality of junctions at points along said tracks and means to cause said toy to change its direction of travel at any of said junctions as desired. 95

3. Apparatus for playing a game including a foundation member, a plurality of sections adapted to be placed side by side and end to end to form said foundation member, a plurality of tracks on each section running in more than one direction, the tracks at the edges of 100 one section coinciding with the tracks at the edges of adjacent sections, a plurality of junctions at points along said tracks, a mechanically propelled toy adapted to travel along said tracks and means to stop said toy 105 and change its direction at said junctions in order that said toy may pass from one track to another. 110

4. Apparatus for playing a game including a foundation member, a plurality of sections adapted to be placed side by side and end to end to form said foundation member, a plurality of tracks on each section running in more than one direction, the tracks at the edges of one section coinciding with the 115 tracks at the edges of adjacent sections, a plurality of junctions at points along said tracks, a mechanically propelled toy adapted to travel along said tracks and a rotatable turn table at said junctions in order that said 120 toy may pass from one track to another. 125

5. Apparatus for playing a game including a foundation member, a plurality of sections adapted to be placed side by side and end to end to form said foundation member, 130

a plurality of tracks on each section running in more than one direction, the tracks at the edges of one section coinciding with the tracks at the edges of adjacent sections, a plurality of junctions at points along said tracks, a mechanically propelled toy adapted to travel along said tracks, a rotatable turn table at said junction and means to stop and re-start said toy at said rotatable turn table so that said toy may pass from one track to another.

6. Apparatus for playing a game including a foundation member, a plurality of sections adapted to be placed side by side and end to end to form said foundation member, a plurality of tracks on each section running in more than one direction, the tracks at the edges of one section coinciding with the tracks at the edges of adjacent sections, a plurality of junctions at points along said tracks, a mechanically propelled toy adapted to travel along said tracks, a rotatable turn table at said junction and means situated adjacent the edge of the foundation member for stopping and allowing said toy to restart at said turn table so that said toy may pass from one track to another.

7. Apparatus for playing a game including a foundation member, a plurality of sections adapted to be placed side by side and end to end to form said foundation member, a plurality of tracks on each section running in more than one direction, the tracks at the edges of one section coinciding with the tracks at the edges of adjacent sections, a plurality of junctions at points along said tracks, a mechanically propelled toy adapted to travel along said tracks, a rotatable turn table at said junction, means to operate said turn table, said operating means being situated at the extremity of said foundation member, means situated adjacent the edges of the foundation member for stopping and allowing said toy to re-start at said turn table so that said toy may pass from one track to another.

8. Apparatus for playing a game consisting of a foundation member formed of a plurality of sections placed edge to edge, standards mounted on said sections, rails mounted on said standards, a model aeroplane and means for causing said model aeroplane to travel along said rails.

9. Apparatus for playing a game consisting of a foundation member formed of a number of sections placed edge to edge, a plurality of standards mounted upon said sections, rails mounted upon said standards to form a number of tracks intercommunicating one with another, a model aeroplane, means to cause said model aeroplane to travel along said rails and means to connect said tracks so that said model aeroplane travels along an uninterrupted track from one section to another.

10. Apparatus for playing a game consisting of a foundation member formed of a number of sections placed edge to edge, a plurality of standards mounted upon said sections, rails mounted upon said standards to form a number of tracks intercommunicating one with another, a model aeroplane, means to cause said model aeroplane to travel along said rails, means to connect said tracks so that said model aeroplane travels along an uninterrupted track from one section to another and means for stopping and re-starting said model aeroplane at the junctions of any two tracks.

11. Apparatus for playing a game consisting of a foundation member formed of a number of sections placed edge to edge, a plurality of standards mounted upon said sections, rails mounted upon said standards to form a number of tracks intercommunicating one with another, a model aeroplane, means to cause said model aeroplane to travel along said rails, means to connect said tracks so that said model aeroplane travels along an uninterrupted track from one section to another, a solenoid situated at the junction of said tracks to arrest the movement of said model aeroplane in order to effect change of direction of said aeroplane.

In witness whereof, I have hereunto signed my name this 26th day of April, 1928.

HARRY FROW COGGON.
